UNITED STATES PATENT OFFICE.

HIRAM WALTERS AND NATHAN BUMPUS, OF CURTICE, OHIO.

EXCAVATING-MACHINE.

1,169,443.

Specification of Letters Patent.

Patented Jan. 25, 1916.

Application filed February 20, 1915. Serial No. 9,485.

To all whom it may concern:

Be it known that we, HIRAM WALTERS and NATHAN BUMPUS, citizens of the United States, and residents of Curtice, in the county of Ottawa and State of Ohio, have invented a certain new and useful Excavating-Machine, of which the following is a full, clear, and exact description of the invention, such as will enable others skilled in the art to which it appertains to make and use the same, reference being had to the accompanying drawings, and the figures of reference marked thereon, which form a part of this specification.

15 Our invention relates to ditching or trench excavating machines of the type employing a rotary excavating wheel and adapted for the digging of either open ditches or trenches or those for receiving drainage tile or the like.

The object of our invention is an improved device to positively maintain the gates closed, during the upward excavating movements of the buckets.

25 The invention is fully described in the following specifications, and while the same, in its broader aspect, is capable of embodiment in numerous forms, a preferred embodiment thereof is illustrated in the 30 drawing.

Referring to the drawing, 1 and 2 in Figure 1, designate parts of the framework of a machine with which the excavating wheel comprising the features of our invention is associated, and 3 one of the supporting wheels of such frame.

35 The excavating wheel is shown as comprising the laterally spaced ring members 4, 4 to which the edges of the excavating buckets 5 are secured as indicated.

40 6, is cutter of the same transverse shape as the buckets 5, also connects the two members 4, in advance of each bucket to form the cutting nose therefor.

45 7, is sets of internal gear teeth secured to rings 4, 4.

8, are pinions, mesh in gear teeth 7, carried in registering position by a drive shaft 9.

50 10, is bearings located on frame part 2 in which drive shaft 9 is journaled.

11, are three idler rolls on outer side rings 4, carried by shaft 12 in bearings 13 on frame part 2, while the lower rolls 11, 55 are mounted on shafts 14, carried by the

pendent bearing parts 15, which are secured to the underside of the frame part 2.

16, are hinged gates, hinged to rear ends of buckets and are extended inwardly to adjacent the inner edges of the ring members 4, 4.

19, is a segmental plate to maintain gates 16 closed during the descending movements of the buckets.

23, is conveyer to deliver excavated matter 65 to one side of the trench.

24, is a segmental plate, located between rings 4, 4 at forward portion of wheel, to prevent an inward dropping of excavated matter, during the upward excavating movements of the buckets.

25, is a cleaning blade between rings 4, 4, carried at the upper end of rod 26, projecting upwardly to positively clean buckets of excavated matter. The rod 26, carries 75 the blade 25 downwardly between frame parts on opposite side of the excavating wheel, between parts 2, 2 as at 27.

28, is a contractile spring anchored to bearing part 15. The spring 28 is to retain 80 the nose of the blade in contact with the outer portions of the buckets.

29, is an adjusting screw to prevent the blade 25 from striking the cutting nose 6 when entering therein.

30 is a trip finger of knife like form, located between rings 4, 4, to open gates 16, when met with blade 25 and is pivoted in vertical bearing 31, which is secured to frame part 2, furnishing bearing for contractile spring 32, which is anchored to 90 30 and 31, and is of suitable strength to revert trip finger 30, after drawn downward with stone or other matter contained in the buckets, that the trip finger 30, cannot cut 95 through.

30, is a trip finger, of knife like form, located between rings 4, 4, secured to segmental plate 24, to open gates 16, when met with blade 25.

33, is the driven sprocket, attached to shaft 36, used for the purpose of conveying chain belt 34, to the point of proximity with hinged gate or end part 16, causing 35 to hold 16 closed from said point of proximity 105 to a predetermined point of discharge.

34, is the rotary chain belt with roller bearings which conveys the power from the driving sprocket 37, on the drive shaft 9, over driven sprocket 33, then with the 110

arc of movement of excavating wheel to sprocket 37.

35, is the lug attached to chain belt 34 which applies the power to 16.

5 36, is a stationary shaft to furnish bearing for driven sprocket 33, in proper place. 37, is the driving sprocket located on driving shaft 9, in the center between pinions 8, 8, which operate in gear teeth 7. Said 10 driving sprocket penetrates segmental plate 24, at point of contact, where it receives chain belt 34. It receives its power from driving shaft 9.

It is thus apparent that we have provided 15 simple, efficient, and inexpensive means for maintaining the bucket gates closed, except during the dumping operation.

Our invention is not limited to any specific construction or arrangement of the 20 parts, except in so far as such limitations are specified in the claims.

Having thus described our invention, what we claim as new and desire to secure by Letters Patent is,—

25 1. The combination of an excavating machine, having buckets thereon with gates hinged to the rear end of each bucket, and

adapted to have its opening and closing movements in the plane of rotation of the wheel, an endless chain belt with lugs attached to act on each of said hinged gates at the lower part of trench to prevent an opening thereof, except at a predetermined point in a revolution thereof.

2. The combination of an excavating machine having buckets thereon with gates hinged to the rear end of each bucket and adapted to have its opening and closing movements in the plane of rotation of the wheel, a driving sprocket applying power 35 to endless chain belt with lugs attached at proper point, to act on hinged gates at lower part of driven sprocket, then with the arc of movement of said wheel to driving sprocket allowing a free opening of said hinged gates.

In testimony whereof we have hereto signed our names to this specification in the presence of two subscribing witnesses.

HIRAM WALTERS.
NATHAN BUMPUS.
